CLAIM

I claim the ornamental design for a GPS receiver with autopilot and integrated lightbar display, as shown and described.

DESCRIPTION

FIG. 1 is an upper right front perspective view of a GPS receiver with autopilot and integrated lightbar display showing my new design, features shown in broken line are for illustrative purposes only and form no part of the claimed design;

FIG. 2 is a lower left rear perspective view thereof;

FIG. 3 is a top plan view thereof;

FIG. 4 is a right side elevational view thereof;

FIG. 5 is a rear plan view thereof;

FIG. 6 is a left side elevational view thereof;

FIG. 7 is a top plan view thereof; and,

FIG. 8 is a bottom plan view thereof.
